CONTROLLING DEVICE

Lajos Wenzler, Augsburg, Germany, assignor to
Uhertype Aktiengesellschaft, Kubli House, Glarus, Switzerland, a corporation of Switzerland

Application February 9, 1935, Serial No. 5,869
In Germany August 30, 1932

10 Claims. (Cl. 74—1)

My invention relates to control devices comprising loose travelling registering members.

The certainty of operation of control devices operating with loose travelling registering balls or the like, such as are employed for photographic type composing apparatus and quite generally in all cases where certain mechanical individual operations have to be controlled step by step in registered succession, may become impaired if the operation of the released registering member differs from the mechanical operation of that successively operating part of the device which serves for the reception of the said registering members. Such cases may, for example, arise when the individual balls are released from their position and raised by hand and are delivered on to a swinging carrier, inasmuch as the mechanical rhythm of the latter cannot be maintained unaltered indefinitely by any human hand, and such cases may likewise occur when the balls roll by virtue of their own weight or have to pass over somewhat varying paths. The danger of these occurrences is avoided, according to the present invention, by this that in the path over which the registering members have to move freely loose spacing members are inserted between the registering members which follow one another step by step, from one spacing to the next.

A preferred embodiment of my invention, particularly suitable for photographic type composing machines, is diagrammatically shown by way of example in the accompanying drawings, in which:

Figs. 1 and 3 show the device in longitudinal section in two different positions,

Fig. 2 shows a detail of the release for the spacing members in a side view,

Fig. 4 is a perspective view of the ball channels of the device showing a spacing member and the pushing or conveying member for the balls, and

Fig. 5 is a plan partly in horizontal section corresponding to Fig. 4.

As shown in the drawings, the registering balls 1 are magazine in the position of rest in an inclined guiding channel 2 behind a bolt 3. By the depression of a key 4 the bolt 3 is withdrawn through the medium of two bell crank levers 5 and 6 and a pull rod 7 so far that a ball 1 is released and rolls forward by virtue of its own weight. Provision is made in known manner to ensure that upon each depression of the key only a single ball is released, whilst the others are held back. The parts by means of which this is accomplished have, for the sake of clarity, not

been shown. When the key 4 is released the bolt 3 is returned by a spring 8 to its original position shown in Figs. 1 and 3. The released ball 1 rolls towards a push member or conveyor 13 operated by the crank drive 9 and 10 of the shaft 11, so that it will slide up and down in a guide 12. The ball is raised by the upper free end of the push member 13 from the lowest position of the latter (Fig. 1) upwards to the discharge channel 14. Fig. 3 shows the push member 13 in proximity to its upper terminal position. The ball deposited in the discharge channel 14 rolls towards its destination where it effects the operation allotted to it in the control of the photographic type composing machine. For the purpose of applying the device to a photographic type composing machine, a plurality of ball channels each associated with its own particular key 4 and its own bolts 3 and so forth, are required for conveying each of the balls 1, as desired, to a particular control place for different printing signs and other arrangements appertaining to the photographic type composing machine. Figs. 4 and 5 show several channels 2 arranged parallel to one another. Each of the channels 2 continues its course in a rectilineal direction through a corresponding discharge channel 14. The pushing member 13 traverses all the channels 2 and 14 and effects the conveyance of the balls on to and along the corresponding rectilineal channel path. The upper edge of the push member 13 terminates in projections or teeth 15 arranged after the manner of a comb and between which the recesses 16 for the balls are formed. The said recesses are arranged in the common channel connecting the channels 2 and 14.

The compositor depresses the key 4 corresponding to the printing sign required, at any given time, whereby he registers the said printing sign through the medium of its channel 2 according to the corresponding ball 1 and by means of the registering operation, after the elapse of a certain time, effects the automatic mechanical photographic operation. The shaft 11 is driven at such a speed as to correspond with the most favourable working rhythm of the photographic type composing machine. For each upward stroke of the pushing member 13 the compositor has to deliver a corresponding ball 1, this being always effected by depressing the corresponding key 4. The operation of the keyboard by hand by the compositor is, however, not eliminated by the constant uniformity of the mechanically operated strokes of the push member. Frequently, the keys of the printing signs which

succeed one another are located on the keyboard at a distance far away from one another, so that the hand of the operator has to pass idly through a considerable distance between two letters, and frequently words occur which can be set up by simply continuously passing over a number of adjacent keys. The present invention fulfills the object of preventing the possibility in the aforesaid extreme cases, of one released ball being retarded or another being accelerated. Any non-uniformity would of necessity give rise to incorrect settings.

The spacing members 17 in the embodiment shown are of comb-like construction so that they can pass through and bridge over several guiding channels. They are actuated and guided by their terminal pins 18 and their projections or teeth 19 engage in the guiding channel 2. Furthermore, they are introduced into the channels 2 just in front of the place where the balls 1 are delivered to the pushing member 13 in order that they may be best adapted to precede the balls.

The spacing members 17, 19 in their inoperative position are situated in the rearwardly and downwardly inclined guide 20 from which they pass automatically in succession into the notches 21 of the star-wheel 23 mounted on the shaft 22. The notches 21 are so shaped that they always engage only one spacing member 17, 19 at its terminal pin 18, closing the guide 20. If, now, the star-wheel 23 is rotated in the direction of the arrow, then the spacing members 17, 19 are automatically and individually successively inserted in a division corresponding to one of the notches 21 of the star-wheel 23, this operation occurring in such a manner that the said spacing members alternate along the path between the star-wheel 23 and the push member 13 with the balls 1. The spacing members 17, 19, for the purpose of their more exact cooperation with the balls 1 also move along the aforesaid path by virtue of their own weight, and for the same purpose they are conveyed back to inoperative position at each stroke effecting the mechanical conveyance of the balls 1. For this purpose there is pivotally mounted on the two sides of the push member 13 at 24 a spring-controlled bell crank lever 25, the deflection of which towards the rear is limited by a pin 26. On the downward stroke of the push member 13 the pins 18 of the spacing members 17, 19 press the bell crank levers 25, which slide past them, forwards, whereupon said bell crank levers 25 swing back underneath the pins 18 so that on the next upward stroke of the push member 13 the said pins 18 are carried upwards by them to such an extent that the spacing members 17, 19 are delivered into the guide 20 as shown in Fig. 3. In this way the spacing members 17, 19 are moved in a cycle and it is only a small number of these spacing members is needed.

Those of the balls 1, which are located in the channel 2 behind the first spacing member 17, 19, cannot roll towards the push member 13 until the spacing member 17, 19, blocking their path thereto, is moved out of the way. Since this is only effected by the uniform strokes of the pushing member, the balls 1, which arrive in succession in the different channels 2 from division to division, can only pass in regular succession corresponding to the strokes of the pushing member 13 on to the latter and thence to the corresponding operative positions. From Figs. 1 and 3 it will be seen that the spacing

members 17, 19 are piled along the channel 2 together with the balls 1 in order that differences of considerable magnitude, which may arise in the release and during the free forward rolling of the balls, may be damped and compensated. A similar piling up of the spacing members 17, 19 may also be provided for at the lower end of the guide 20.

The operative path of the spacing members 17, 19 is shorter than the corresponding path over which the balls 1 have to move, so that the spacing members 17, 19 can each be inserted in advance of each ball 1, if the said spacing members are released simultaneously with the balls. The reliability of this operation is further increased by this that the spacing members 17, 19 are released by the same depression of the key as the corresponding balls 1, but in advance of the latter.

An arrangement of this kind is provided in the embodiment shown, in the following manner: The continuously rotating shaft 11 drives through the medium of the transmission 27, 28, 29 not only the star-wheel 23 but also the ratchet wheel 30 (Fig. 2) mounted on the shaft 22 of the star 25 wheel, which ratchet wheel is engaged by a fork 32 oscillating about an axle 31. The fork 32 is provided with an extension in the form of a lower arm 33, in which a transverse rod 34 is fixed. The other end of this transverse rod 34 is fixed 30 in a lateral arm 35 (Fig. 1) which likewise oscillates about the axle 31. All the bell crank levers 6, which appertain individually to one of the channels 2 and which are arranged one below the other in the same row, bear against the transverse rod 34 so that whichever key 4 is depressed, upon the oscillating movement of the corresponding bell crank lever 6, the fork 32 is swung about its axle 31 at the same time. Upon the release of the key 4 depressed at any given time, 40 the fork 32 swings back automatically into the position of rest shown in Fig. 2 under the action of a spring control not shown. The operation of the spacing members 17, 19 is thus controlled by means of the ratchet wheel 30 in such a manner that the star wheel 23 can, upon each to-and-fro movement of the fork 32, i. e. on each depression of the key, only turn onwards to the extent of one spacing or division, and consequently can only receive from the guide 20 and 50 insert in the channels 2 one spacing member 17, 19 in each instance. The adjustment is such that the star wheel 23 is turned somewhat in advance of the complete withdrawal of the bolt 3. The driving belt 28 is arranged in such manner that 55 it can slip somewhat and consequently can compensate for the small irregularities which may occur in it.

The device described bridges over, as it were, the difference between the entirely free and the 60 entirely mechanical condition of the registration effected by means of the loose balls or the like, and provides in a kind of loosely mixed pre-registration an intermediary agent which ensures the strict co-ordinated succession of the registering 65 members which are controlled with regard to their positioning, and likewise permits the correction of the initial arrangement of the latter up to the last moment, inasmuch as the balls or the like in front of the pushing member 13 may, if 70 desired, be made accessible at all points.

I claim as my invention:

1. A control mechanism, comprising loose registering elements adapted to freely move by gravity along definite paths, a rhythmically moving 75

- member for uniformly conveying said registering elements to their operative positions, loose spacing elements, and means for feeding said spacing elements into position to successively advance by gravity in between two registering elements. 5
2. A control mechanism, comprising loose registering elements adapted to freely move by gravity along definite paths, a rhythmically moving member for uniformly conveying said registering elements to their operative positions, loose spacing elements, and stepwise operated means for feeding said spacing elements into position to successively advance by gravity in between two registering elements in alternate position there- 10 with. 15
3. A control mechanism as specified in claim 12, wherein the operative path travelled by said spacing elements is shorter than the corresponding path of said registering elements. 20
4. A control mechanism, comprising a rhythmically moving member, loose registering elements adapted to freely move by gravity along definite paths to be uniformly conveyed by said rhythmically moving member to their operative positions, 25 means for releasing said registering elements, loose spacing elements cooperating with said registering elements, means for feeding said spacing elements into position to successively advance by gravity in between two registering elements, and a single means for controlling the release of said 30 registering elements and the feeding of said spacing elements. 35
5. A control mechanism as specified in claim 15, in which the releasing of said registering elements and the feeding of said spacing elements are so timed as to enable said spacing elements to be moved into position in advance of said registering elements. 40
6. A control mechanism, comprising a plurality of loose registering elements, a plurality of parallel guiding channels enabling said registering elements to move along freely by gravity, a rhythmically moving member for uniformly conveying said registering elements to their operative positions, a plurality of loose comb-like spacing elements traversing said channels so as to 45 engage the registering elements therein, and stepwise moving feeding means for feeding said spacing elements into position to successively move by gravity across the channels in alternating relation with said registering elements, the 5 comb-like projections of the various spacing elements being always in advance of the corresponding registering elements. 10
7. A control mechanism, comprising a plurality of loose registering elements a plurality of parallel guiding channels therefor enabling said registering elements to move along freely by gravity, a rhythmically moving member for uniformly conveying said registering elements to their operative positions, a plurality of loose comb-like 15 spacing elements traversing said channels, the comb-like projections engaging said registering elements therein, said spacing elements having at each end a guiding pin, rotatable recessed wheels adapted to engage said pins for feeding 20 said spacing elements into position to successively move by gravity across said channels in alternate relation with said registering elements, the comb-like projections of said spacing elements engaging said registering elements in advance thereof. 25
8. A control mechanism as specified in claim 7, including a ratchet device operatively associated with said rotatable recessed wheels controlling their stepwise rotation. 30
9. A control mechanism, as specified in claim 7, including a means for successively releasing said registering elements, and a ratchet device operatively associated with said rotatable recessed wheels controlling their stepwise rotation, and a single means for operating said releasing means 35 and said ratchet device, the operation of the latter and said releasing means being so timed as to enable one of said spacing elements always to be fed in advance of a row of registering elements. 40
10. A control mechanism as specified in claim 1, including a means on said rhythmically moving member so disposed as to always automatically return said spacing elements to their original positions. 45
